CLAIM

The ornamental design for a feeder, as shown and described.

DESCRIPTION

FIG. 1 is a front, right, and top perspective view of a feeder, showing my new design;

FIG. 2 is a rear, left, and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view taken from the encircled portion labeled "9" in FIG. 1; and,

FIG. 10 is an exploded view of the feeder.

The dot dash broken lines in FIGS. 1 and 9 denote the boundaries of the encircled portion and form no part of the claimed design. The evenly spaced broken lines in the drawings depict portions of the feeder that form no part of the claimed design.
